CLAIM

The ornamental design for a communication device, as shown and described.

DESCRIPTION

FIG. 1 is a perspective view of a communication device showing the claimed design;

FIG. 2 is a front view thereof;

FIG. 3 is a rear view thereof;

FIG. 4 is a first side view thereof;

FIG. 5 is a second side view thereof;

FIG. 6 is a top view thereof; and

FIG. 7 is a bottom view thereof.

FIG. 8 is a perspective view of the communication device of FIG. 1, showing the compartment in an open position;

FIG. 9 is a front view thereof;

FIG. 10 is a rear view thereof;

FIG. 11 is a first side view thereof;

FIG. 12 is a second side view thereof;

FIG. 13 is a top view thereof; and,

FIG. 14 is a bottom view thereof.

The broken lines shown in the drawings are for the purpose of illustrating unclaimed portions of the communication device and form no part of the claimed design.
